CLAIM

The ornamental design for a connector for joining multiple picture frames, as shown and described.

DESCRIPTION

FIG. 1 is a front perspective view of a connector for joining multiple picture frames showing my new design, this embodiment being shown in a transparent or translucent material.

FIG. 2 is a front elevational view thereof.

FIG. 3 is a back view thereof.

FIG. 4 is a right side view thereof, the left side view being a mirror image thereof.

FIG. 5 is a top view thereof, the bottom view being a mirror image thereof.

FIG. 6 is a front perspective view of a second embodiment of a connector for joining multiple picture frames showing my new design, this embodiment being shown in an opaque material.

FIG. 7 is a front elevational view of this second embodiment.

FIG. 8 is a back view of this second embodiment.

FIG. 9 is a right side view thereof, the left side view being a mirror image of this second embodiment; and,

FIG. 10 is a top view thereof, the bottom view being a mirror image of this second embodiment.
